his Attorney.

UNITED STATES PATENT OFFICE

2,303,044

AUTOMATIC SIPHON BREAKER FOR
FLUSH VALVES

Joseph J. Goodrie, Chicago, Ill., assignor of
twenty-five per cent to Albert J. Fihe, Chicago,
Ill.

Application July 19, 1941, Serial No. 403,193

5 Claims. (Cl. 137—69)

This invention relates to an improved automatic siphon breaker for flush valves, and the present invention constitutes an improvement over my prior patents on similar devices, one entitled "Unitary flush valve connection," No. 2,134,182, granted October 25, 1938, and the other entitled "Fixed vacuum breakers for flush valves," No. 2,151,200, granted March 21, 1939.

One of the important objects of this invention is to provide means for breaking the siphon or vacuum which is sometimes created in water systems of buildings, particularly taller buildings when the water pressure is shut off or reduced and which would ordinarily have a tendency to carry flush water from toilet bowls or the like back into the system.

Another object of the invention is to provide a device that can be used interchangeably on all types of flush valves for toilet bowls, laboratory equipment, hospital apparatus or the like.

It is known to be true especially in the larger buildings that, when the main water supply is shut off for some reason or another, a suction or vacuum is created when a faucet, valve or the like is turned on, and one of the objects of this invention is to provide a means of breaking this vacuum and thus prevent any back seepage or contamination of the incoming flow of water.

Another object of this invention is to provide an apparatus that is unitary in construction.

Another important object of the invention is to provide a device that can be used on either high or low pressure types of toilet bowls or the like without any undue change in the construction of the invention.

Still another important object of the invention is to have no moving parts therein which may stick through disuse or which may have dirt collect thus causing the movement to stop.

Another and still further object of the invention includes the provision of means whereby the flow of incoming water to the toilet bowl or other similar equipment will always be under control.

In installations of this sort, it often happens that the water from toilet bowls or similar equipment such as various apparatus in hospitals, laboratories and the like is drawn upwardly and outwardly therefrom back into the main water line, this occurring quite frequently when the water supply is shut off for some reason or another, whereupon the opening of a faucet or valve at some lower level will immediately create a suction or back pressure, and unless some means exists in the inlet pipe for breaking such a vacuum, the contaminated waste water from the toilet

bowl or other apparatus is drawn back into the main supply line whence it is then delivered to other outlets and may inadvertently be used for drinking or other purposes, thereby constituting a serious detriment to health.

Other and further important objects of the invention will be apparent from the disclosures in the accompanying drawing and following specification.

10 The invention, in a preferred form, is illustrated in the drawing and hereinafter more fully described.

In the drawing:

15 Figure 1 is a top plan view of the improved automatic siphon breaker of this invention.

Figure 2 is a sectional view taken on the line 2—2 of Figure 1, showing the interior construction of the device.

20 Figure 3 is a horizontal section taken on the line 3—3 of Figure 2, looking in the direction indicated.

Figure 4 is a partial section and parts being broken away taken on the broken line 4—4 of Figure 2, looking in the direction indicated.

25 Figure 5 is a side view of the improved automatic siphon breaker for flush valves of this invention.

As shown in the drawing:

30 The reference numeral 10 indicates generally the casing of the improved automatic siphon breaker of this invention, the same being provided at its top with an attachment 12 whereby the device may be connected into a pipe line or the like, and the body 10 is screw-threaded at its lower end as shown at 44 for a similar connection at this point.

The casing 10 has an inside element 16 which forms an inner wall and divides the casing into two parts, each comprising a passageway for water.

40 The central passageway includes a restricted pipe or nozzle element 18 which is screw-threadedly mounted in position in a ledge 20 integral with the casing 10 and which is shaped as shown to provide a constricted stream when water flows therethrough.

45 Just below the ledge or element 20, there is fashioned in the casing 10 an opening or slot 22 which is for the purpose of allowing incoming atmospheric air for siphon breaking action.

A plug 24 is removably mounted below the element 18 and also has a restricted passageway therethrough as best illustrated in Figure 2.

The casing 10 is provided with an opening at one side adjacent the upper portion thereof, and

this is normally closed by means of a plug 26 which is screw-threadedly mounted therein by an adjusting screw or the like 28. This screw is held in desired position by means of a lock nut 30 and a cap 32 is provided over the assemblage in order to keep out dirt or other foreign material.

Adjacent the inner end of the adjusting screw 28 is a valve element 34 hingedly mounted on a pin or the like 36 and adapted to operate against a seat 38 formed in the body of the casing 10.

In operation, the device is placed in position below a flush valve and above an ordinary toilet bowl or in some similar relationship with a sink or other similar apparatus. In operation, water enters the top of the device, and some of it passes through the restricted passage 18 and the element 24. The main operation of the water opens the valve 34 and flows through the passageway between the walls 10 and 16 of the casing, providing a desirable flushing action for the toilet bowl or similar device. The set screw 28 can be so adjusted that the valve 34 will open a desired amount, and the plugs 18 and 24 with the passageway therethrough can be removed, and other plugs with differently sized or shaped passageways substituted depending upon the particular type of system with which the device is to be used such as, for example, a high pressure or a low pressure system for flush valves or similar devices.

No splashing or other undesirable excretion of water will take place through the slot 22 because the nozzle 18 is so shaped and situated that this is rendered practically impossible.

On the other hand, if a vacuum or suction is created in the feed pipe leading to the device, this suction or vacuum will be immediately broken by the entry of atmospheric air through the slot 22, and there will consequently be no siphoning action of water from the toilet bowl or similar device up through the flush valve and into the pipe line or other water system whence it can, when the pressure is again turned on, find its way to faucets, drinking fountains and the like.

It will be obvious that herein is provided an automatic siphon breaker for flush valves used with toilet bowls or in similar situations which should be eminently satisfactory in that it is simple of construction, readily installed, has comparatively few parts and practically no moving parts and consequently, can, under practically no circumstances, ever get out of order. Furthermore, the device can be readily adjusted or changed to accommodate many and various types of flush bowls and flushing systems with a very small expenditure of time and labor and with practically no extra parts or substituted parts.

I am aware that many changes may be made and numerous details of construction varied throughout a wide range without departing from the principles of this invention, and I, therefore, do not purpose limiting the patent granted hereon otherwise than as necessitated by the prior art.

I claim as my invention:

1. An automatic siphon breaker for flush valves and toilet bowls comprising a casing, an extraneous passageway for a portion of the water stream around the central portion of the casing, a valved port communicating with such extraneous pas-

sageway, a hinged valve mounted over the port, an adjustable stop in juxtaposition with the valve, and nozzle means in the central part of the casing for providing a restricted flow of the remainder of the water stream through said central part.

2. An automatic siphon breaker for flush valves and toilet bowls comprising a casing, an extraneous passageway for a portion of the water stream around the central portion of the casing, a valved port communicating with such extraneous passageway, a hinged valve mounted over the port, an adjustable stop in juxtaposition with the valve, and nozzle means in the central part of the casing for providing a restricted flow of the remainder of the water stream through said central part together with a slot open to the atmosphere adjacent the nozzle.

3. An automatic siphon breaker for flush valves and toilet bowls comprising a casing, an extraneous passageway for a portion of the water stream around the central portion of the casing, a valved port communicating with such extraneous passageway, a hinged valve mounted over the port, an adjustable stop in juxtaposition with the valve, and nozzle means in the central part of the casing for providing a restricted flow of the remainder of the water stream through said central part together with a slot open to the atmosphere adjacent the nozzle, said slot being positioned in the casing and above the lower end of the nozzle.

4. An automatic siphon breaker for flush valves and toilet bowls comprising a casing, an extraneous passageway for a portion of the water stream around the central portion of the casing, a valved port communicating with such extraneous passageway, a hinged valve mounted over the port, an adjustable stop in juxtaposition with the valve, and nozzle means in the central part of the casing for providing a restricted flow of the remainder of the water stream through said central part together with a slot open to the atmosphere adjacent the nozzle, said slot being positioned in the casing and above the lower end of the nozzle, and a further restricted passageway means in the casing below the slot and below the first nozzle.

5. An automatic siphon breaker for flush valves and toilet bowls comprising a casing, an extraneous passageway for a portion of the water stream around the central portion of the casing, a valved port communicating with such extraneous passageway, a hinged valve mounted over the port, an adjustable stop in juxtaposition with the valve, and nozzle means in the central part of the casing for providing a restricted flow of the remainder of the water stream through said central part together with a slot open to the atmosphere adjacent the nozzle, said slot being positioned in the casing and above the lower end of the nozzle, and a further restricted passageway means in the casing below the slot and below the first nozzle, said further means comprising a removable plug having a central passageway therethrough, said passageway being in line with the passageway in the first-named nozzle.

JOSEPH J. GOODRIE.
